J. POCHOPEN,
BATH TUB CABINET,
APPLICATION FILED DEC. 28, 1917.

1,272,087.

Patented July 9, 1918.

UNITED STATES PATENT OFFICE.

JOHN POCHOPEN, OF FLINT, MICHIGAN.

BATH-TUB CABINET.

1,272,087.

Specification of Letters Patent.

Patented July 9, 1918.

Application filed December 28, 1917. Serial No. 209,249.

To all whom it may concern:

Be it known that I, JOHN POCHOPEN, a citizen of Russia, residing at Flint, in the county of Genesee and State of Michigan, have invented certain new and useful Improvements in Bath-Tub Cabinets, of which the following is a specification.

This invention relates to certain new and useful improvements in bath tub cabinets.

10 The primary object of the invention is the provision of a cabinet of general utility especially adapted for employment in a small bedroom and accommodating a bath tub therein for ready use when desired 15 without the necessity of having a bathroom.

A further object of the device is the provision of a bedroom cabinet or washstand adapted to removably hold a bath tub normally concealed therein and readily po-

20 sitionable for immediate use when desired.

A still further object of the device is to provide a cabinet that is easy and inexpensive to manufacture but which possesses great strength, the same being adapted for 25 housing a bath tub automatically removed therefrom upon opening the cabinet and readily positioned therein when not in use.

In the drawing forming a part of this application and in which like designating 30 characters refer to corresponding parts throughout the several views,

Figure 1 is a front elevation of the device.

Fig. 2 is a vertical transverse sectional view thereof.

35 Fig. 3 is a horizontal sectional view of the same in its open arrangement showing the tub removed.

Fig. 4 is a detail vertical sectional view of one of the tub moving members, and

40 Figs. 5 and 6 are perspective views of the hinge members and track members provided in the device.

Referring more in detail to the drawing, the cabinet 10 is provided having the general form of a washstand with a sliding drawer 11, a table top 12 and a back 13. A compartment 14 is arranged in the lower part of the cabinet having track rails 15 transversely positioned upon the bottom 16

50 of the cabinet formed with projecting ends 17 at the forward open side of the cabinet.

An approach or board 18 is arranged for the front opening of the cabinet having slots 19 for accommodating the rail ends 17 55 when the approach is closed as best illustrated in Fig. 2 of the drawing, the said ap-

proach being hinged by means of a rod 20 carried by the cabinet bottom 16.

Rail members 15' are provided upon the approach 18 forming continuations of the 60 rails 15 when the approach is in its open slightly forwardly inclined arrangement. Swinging doors 21 are hinged as at 22 to the opposite sides of the cabinet for closing upon the approach 18, when the latter is 65 closed and adapted to be retained in closed arrangement by means of a latch 23. A bath tub 24 arranged with rollers 25 upon the bottom thereof is adapted for positioning within the compartment 14 upon the 70 track 15 for traveling downwardly over the rails 15 of the approach 18 when the latter is open. A plurality of springs 26 are secured within cups 27 upon the rear wall 28 of the cabinet within the compartment 14 75 for bearing against the adjacent side of the tub 24, with said springs compressed against the tub when the approach 18 is closed as well as the doors 21.

A suitable pipe connection 29 is arranged 80 for the tub 24 for supplying water thereto and it will be apparent that with the device normally positioned as shown in Fig. 2 of the drawing, the doors 21 can be opened permitting the approach 19 to be swung downwardly in contact with the floor 30 while the springs 26 will forwardly impel the tub 24 upon the track 15—15', until the tub travels down the approach 18 to a point upon the floor 30 where the same may be readily used 85 with the water supplied from the pipe 29. The tub 24 is again repositioned in the compartment 14 when desired and the approach 18 moved upwardly permitting the doors 21 to be closed and locked. A serviceable cabinet 90 is arranged which may be readily employed for furnishing a bath tub 24 in compact arrangement, automatically positioned upon the floor for use by opening the doors of the cabinet. It will be seen that by reason 100 of the slots 19 of the approach 18 and the extensions 17 of the tracks 15 that there is only an immaterial gap between the adjacent ends of the track sections when the device is open for use.

105 What I claim as new is:—

1. A device of the class described comprising a cabinet having a compartment adjacent the bottom thereof, rails upon the bottom of the compartment having forward 110 extensions adjacent the open front of the cabinet, an approach hinged to the bottom

of the cabinet arranged with slots adapted for the reception of the said rail extensions when the device is closed, closing doors for the cabinet positioned outwardly of the approach when closed, a tub slidably mounted upon the track within the compartment and automatic projecting means for the tub arranged within the cabinet.

2. A device of the class described comprising a cabinet having a compartment provided with a bottom and having a front opening, track rails transversely arranged upon the bottom of the cabinet having forwardly projecting ends, an approach hinged to the bottom of the cabinet arranged with

slots adapted for the reception of the said track ends when the device is closed, rails upon said approach adjacent the said slots arranged in substantial alinement with the rails of the cabinet bottom when the approach is in its open slightly inclined position, a concealed tub movably mounted upon the rails within the cabinet when the latter is closed, expelling springs carried by the back of the cabinet in contact with the tub when the device is closed and a retaining catch for the cabinet doors.

In testimony whereof I affix my signature.

JOHN POCHOPEN.
